UNITED STATES PATENT OFFICE

2,506,685

SHOULDER-SUPPORTED FLASHLIGHT HOLDER

Stanley P. Sadloski, New Britain, and Peter Checkowitz, Hartford, Conn.

Application October 19, 1948, Serial No. 55,304

5 Claims. (Cl. 240—59)

1

This invention relates to flashlight holders, and more particularly to a holder adapted to support a flashlight adjustably upon the shoulder of the user, thus leaving his hands free to manipulate tools.

One object of this invention is to provide a device of the above nature which includes a pair of curved adjustable support members adapted to resiliently grip the shoulder of the user.

Another object is to provide a device of the above nature which has a base member which slidably connects the support members permitting the device to be readily collapsed so as to occupy a small space when not in use.

A further object is to provide a device of the above nature which will be simple in construction, inexpensive to manufacture, easy to use and manipulate, compact, ornamental in appearance, and very efficient and durable in use.

With these and other objects in view, there has been illustrated on the accompanying drawing one form in which the invention may conveniently be embodied in practice.

In the drawings:

Fig. 1 is a perspective view showing the improved flashlight holder as it appears when supported upon the shoulder of the user.

Fig. 2 is a front elevation of the holder on an enlarged scale.

Fig. 3 is a fragmentary side view of the same.

Fig. 4 is an oblique top view showing the base member and portions of the support members engaged therein.

The improved flashlight holder will be found useful by electricians, motorists, fishermen, and others who may need to have the use of both hands while relying upon a flashlight for illumination.

Referring now to the drawings, in which like reference numerals denote corresponding parts throughout the several views, the numeral 10 indicates generally the improved holder which comprises a pair of U-shaped support members 11, 12 preferably constructed of heavy rods and having pairs of downwardly-curved and substantially parallel arms 13, 14, respectively. The support members 11, 12 also have outer closed ends 15 which carry tubular rubber friction elements 16, and are reversely bent or kinked in order to hold said elements 16 against rotation.

The support members 11, 12 extend outwardly and downwardly from a flat base member 17 having a pair of opposite reduced side lugs 18. The respective outer ends of the lugs 18 are provided with a pair of parallel horizontal apertures

2

19, in which the upper ends of the support arms 14 are fixed by means of cross pins 20.

The arms 13 of the support member 11 are slidably held in a pair of parallel horizontal apertures 21 formed in the side lugs 18 inwardly of the apertures 19, and are provided at their ends with transverse guide loops 22 slidably engaging the arms 14, whereby separation of the support member 11 from the base member 17 will be prevented. The support arms 13 preferably are made slightly divergent whereby they will engage in the apertures 21 with sufficient friction to prevent any accidental change of adjustment of the support member 11.

15 The base member 17 is provided with a flashlight gripping device 23 comprising an upstanding semi-circular spring clip 24, the upper ends of which carry a pair of tubular gripping elements 25, preferably of rubber, adapted to hold 20 a flashlight F therein, as shown in dotted lines in Fig. 3.

25 A stem 26 extends downwardly from the U-shaped clip 24 and terminates in a ball 27 which is seated in a concave socket 28 formed centrally in the upper surface of the flat base member 17.

30 The ball 27 is adapted to be adjustably held by means of an angular locking clamp 29, the outer end of which has a bottom bearing portion 30 for engagement with the upper surface of the base member 17. The inner end of said clamp has a pair of spaced fingers 31 which embrace the ball 27.

35 The clamp 29 is secured to the base member 17 by means of a thumb screw 32 which extends downwardly through a central portion of said clamp and is engaged in a tapped aperture 33 in the base member 17. By means of this construction, the flashlight gripping device 23 may be rotated to place it in any desired adjusted position, where it will be held by tightening the thumb screw 32.

40 In order to positively prevent the flashlight holder 10 from falling from the user's shoulder if he should be working in a bent-over position, the support member 12 may be formed with a side loop 34 to which one end of a cord 35 is secured. The cord 35 preferably will be passed around the user's body and has a snap hook 36 at its other end, whereby said cord is adapted to be attached to a side loop 37 formed in the support member 11.

Operation

45 In use, the holder 10 will be adjusted by slid-

ing the support arms 13 in the apertures 21 until the friction elements 16 are suitably disposed to grip the shoulder of the user. A flashlight may then be inserted in the gripping device 23, which will be adjusted to the proper angle to throw the light in the desired direction, after which the thumb screw 32 will be tightened so that further movement of the ball 27 will be prevented.

The cord 35 will be passed around the user's body and attached to the loop 37 by means of the snap hook 36, in order to provide additional security.

When not in use, the support arms 13 may be slid inwardly in the apertures 21 so that the holder will be collapsed into a minimum of space.

While there has been disclosed in this specification one form in which the invention may be embodied, it is to be understood that this form is shown for the purpose of illustration only, and that the invention is not to be limited to the specific disclosure, but may be modified and embodied in various other forms without departing from its spirit. In short, the invention includes all the modifications and embodiments coming within the scope of the following claims.

Having thus fully described the invention, what is claimed as new, and for which it is desired to secure Letters Patent, is:

1. In a flashlight holder, a pair of curved oppositely extending U-shaped support members having parallel arms, an apertured base member receiving said arms slidably connecting said support members in overlapping relationship, and a flashlight gripping device secured to said base member, whereby the support members are adapted to engage the shoulder of the user while supporting a flashlight above the shoulder.

2. The invention as defined in claim 1, in which the outer ends of said support members are pro-

vided with reverse bends and tubular friction elements thereon.

3. The invention as defined in claim 1, in which one of said support members is provided with a pair of guide loops at the ends of the arms thereof, said loops slidably embracing the arms of said other support member.

4. In a flashlight holder, a base member, a pair of curved U-shaped wire support members extending in opposite directions from said base member, said support members having parallel pairs of overlapping arms received in apertures in opposite sides of said base member, the arms of one of said support members being frictionally and slidably held in said base member, a flashlight gripping device, and means adjustably securing said gripping device to said base member.

5. The invention as defined in claim 4, in which said base member has a flat upper surface and said flashlight gripping device comprises a ball which is seated in a central spherical recess in said upper surface, and an angular clamp held against said ball and said upper surface by a screw.
